ATTY.

UNITED STATES PATENT OFFICE

AXEL WASBERG, OF CHICAGO, ILLINOIS, ASSIGNOR TO CAMEL COMPANY, OF CHICAGO, ILLINOIS, A CORPORATION OF ILLINOIS

DOOR ELEVATING MECHANISM

Application filed August 7, 1930. Serial No. 473,733.

This invention relates generally to door elevating mechanism and contemplates more specifically the application of such mechanism in connection with side slide doors employed on railway house cars.

It has been proposed, heretofore, to provide lifting mechanism for sliding doors for house cars, comprising essentially a runway pivoted eccentrically to the door and provided with antifriction elements in contact therewith, upon which the door is supported for sliding movement. In its lowered position the door is usually supported frictionally upon a fixed track, upon which the anti-friction elements are adapted to roll. To actuate the runway for elevating the door above the track and for supporting it for movement upon the anti-friction elements an operating lever is usually employed. It is to the construction of such an operating lever and its relationship to the remainder of the elevating mechanism and to the door that this invention is particularly directed.

The invention has for an object the provision of door elevating mechanism, including an operating lever adapted to lift the door by an outward pull on the lever.

It is an object to provide door elevating mechanism in which an operating lever adapted to be moved away from the door in the lifting movement thereof is designed to lie normally in a substantially horizontal plane.

An object, furthermore, is the provision of door elevating mechanism embodying a lever capable of being operated with equal facility both from the ground and from a loading platform.

An object, also, is the provision of door elevating mechanism in which means is provided between the door and said mechanism adapted to prevent relative horizontal and vertical movements therebetween.

Other objects and advantages will become more apparent as the description of the invention proceeds.

In the accompanying drawings illustrating a preferred embodiment of the invention, Figure 1 is a fragmentary elevation of a

house car side illustrating a sliding door to which the invention is applied.

Figure 2 is a sectional view taken on line 2—2 of Figure 1, illustrating the door in its lowered position.

Figure 3 is a sectional view similar to Figure 2 but illustrating the door in its elevated position.

Figure 4 is a sectional view taken on line 4—4 of Figure 1.

Mounted on the car siding 10 of a railway house car there is disclosed, in a preferred embodiment of the invention, a door 11 which may be of any desired construction and is illustrated in Figure 1 as a corrugated metallic door. Gussets 12 and 13, constituted preferably of castings, are shown secured to the lower corners of the door. These gussets are provided with pads 14 and 15 adapted to be supported upon and frictionally engage a fixed track 16. This track is supported in position by means of a plurality of brackets 17 secured to the track and to the car.

Elevating mechanism is provided for the door in order to disengage the frictional engagement between the door and the track when it is desired to move the door toward open or closed position. This elevating mechanism comprises a runway 18, in which anti-friction elements 19—19 are seated. These elements, in the present instance, are shown as balls. Castings 20—21 are secured to the ends of the runway and are provided with trunnions 22—23 adapted to be received in bearings 24—25 formed in the gusset members 12 and 13.

Referring to Figure 4 of the drawings it will be observed that the trunnions are positioned eccentrically relative to the axis of the runway so that an eccentric connection between said runway and the door is provided. These castings are provided with lugs 26, adapted as hereinafter explained, to serve as stop members. A spacer 27 is disclosed, positioned within the runway and provided at its ends with pairs of downwardly extending lugs 28—29 which engage the antifriction elements and maintain them in the desired spaced relation. Secured as by rivets

to the upper portion of the runway 18 is a bracket 30 provided with an elongated slot 31. Extending through the slot 31 is an operating lever 32 provided at its free end with a handle 33 and at its other end with an eye portion 34. A member 35 is secured to the door and is provided with an eye portion 36 with which the eye portion 34 of the operating lever 32 is adapted to have loose engagement.

10 A bearing member 37 is rigidly secured to the door. This bearing member extends through a coped or cut-out portion in the rear of the runway 18 and is provided with a hook portion 38. Extending across the coped portion of the runway is a substantially cylindrical member 39, the ends of which are riveted to the runway. This member is adapted to be seated within the bearing member 37 and be embraced by the hook portion of said bearing member.

15 From the foregoing description of the invention it is believed that the operation of the structure set out will be apparent. 20 When it is desired to elevate the door for movement relative to the fixed track the operator grasps the handle 33 of the lever 32 and exerts an outward pull thereon. The lever will thereupon engage the bracket 30 25 rigidly secured to the runway and impart to said runway a transverse oscillatory movement about the antifriction elements as fulcrums. Such movement of the runway will necessarily, due to the eccentric connection 30 between it and the door, impart a lifting movement to the door, whereupon the weight thereof will be supported upon the balls for sliding movement relative to the track. In the transverse movement of the runway the 35 stop members 26 will engage the pads 14 and 15 of the gusset members 12 and 13 in order to limit the elevating movement of the door. It is evident that a lifting movement may be imparted to the door as readily from a 40 platform as from the ground. When the door is operated from a platform it is only necessary to initially raise the operating lever 32 to the angular position shown in dotted lines in Figure 1, whereupon the door may be 45 readily elevated. This position of the operating lever may be had because of the elongated slot provided in the bracket 30.

50 It is evident, because of the loose or pivotal connection between the eye of the operating lever 32 and the door, that as the free end of the lever is pulled outwardly a force is exerted tending to separate the door and the runway. In order to counteract this force the hook portion 38 is provided on the bearing member 37. It is apparent, also, that due to the great weight of the door and the position of the anti-friction elements there may possibly be a tendency for the runway to bow upwardly. Such a tendency is also 55 counteracted by means of the bearing mem-

ber 37 through engagement thereof with the cylindrical member 39 secured to the runway. It is to be understood, however, that the cylindrical member and the bearing member do not normally aid in the lifting of the door. The elevating movement of the door is produced by means of the eccentric connections hereinbefore referred to. Of course, in the event of any upward bowing of the runway it is possible that the members 37 and 39 may, 70 to some extent, aid in elevating the door but such aid is not relied upon. 75

80 It is apparent that numerous changes in the details illustrating the preferred form of the invention may be made without departing from the spirit thereof, as set out in the claims appended hereto.

I claim:

1. In door elevating mechanism, the combination with a runway pivoted eccentrically to said door, of actuating means for said runway, said means comprising a bracket member secured to the runway and having a slot and an operating lever pivoted to said door and extending through said slot, said slot being substantially vertical and said lever lying normally in a substantially horizontal plane, whereby said lever is operable from the ground or from a platform. 85

2. In door elevating mechanism, the combination with a runway pivoted eccentrically to said door, of actuating means for said runway, said means comprising a bracket member secured to the runway and having a slot and an operating lever pivoted to said door and extending through said slot, said lever being adapted to be pulled outwardly away from the door whereby transverse movement is imparted to said runway through said bracket for elevating the door. 90

100 3. Door elevating mechanism comprising, in combination, a runway pivoted eccentrically to said door and actuating means for said runway, said means including a bracket secured to said runway and an operating lever pivoted to said door, said lever being engageable with said bracket by an outward pull away from said door to rotate said runway and elevate the door, and means preventing separation of said runway and said door. 105

110 4. Door elevating mechanism comprising, in combination, a runway pivoted eccentrically to said door and actuating means for said runway, said means including a bracket secured to said runway and an operating lever pivoted to said door, said lever being engageable with said bracket by an outward pull away from said door to rotate said runway and elevate the door, and means preventing separation of said runway and said door, said last mentioned means comprising a member carried by said runway and a member secured to said door having a hook-shaped portion engaging said first mentioned member. 115

120

125

130

5. In combination, a sliding door, a track therefor, said door being normally in frictional engagement with said track, a runway having eccentric pivotal connection with said door, anti-friction elements upon said track and contacting with said runway, a bracket provided with a slot secured to said runway, an operating lever pivoted at one end to said door and extending through said slot, said lever, upon outward pull thereof away from the door, being adapted to oscillate said runway through said bracket, whereby said door is raised above said track and is supported upon said anti-friction elements for sliding movement on the track.

6. Door elevating mechanism comprising, in combination, a runway pivoted eccentrically to said door and actuating means for said runway, said means including a bracket secured to said runway and an operating lever pivoted to said door, said lever being engageable with said bracket by an outward pull away from said door to rotate said runway and elevate the door.

25 Signed at Chicago, Illinois, this 30th day of July, 1930.

AXEL WASBERG.
